UNITED STATES PATENT OFFICE

2,598,801

LUBRICATING APPARATUS FOR INTERNAL-
COMBUSTION ENGINES AND THE LIKE

George M. Krug, Canton, Ohio, assignor to Hercules Motors Corporation, Canton, Ohio, a corporation of Ohio

Application December 24, 1949, Serial No. 134,901

15 Claims. (Cl. 184—6)

1

The invention or discovery relates to lubrication apparatus for internal combustion engines and the like, and more particularly for internal combustion engines which are adapted for unattended operation over relatively long periods of time, which may be as long as six months. For such unattended operation of an internal combustion engine, it is a requirement that the lubrication apparatus for the engine be capable of functioning properly not only for the desired period but also in such manner as to maintain the temperature of the lubricant, usually oil, below a definite maximum such as in the neighborhood of 170° F.

Prior to the present improvements, efforts made to produce internal combustion engines adapted for unattended operation for a period of as long as six months have not been successful to the desired extent, and in particular great difficulty has been encountered in providing suitable lubrication apparatus for such an engine.

The objects of the present invention or discovery include the provision of improved lubrication apparatus particularly adapted for use in an internal combustion engine which is adapted for unattended operation for a period of as long as six months and for operation in which the temperature of the lubricant is maintained below a definite maximum such as in the neighborhood of 170° F.

The foregoing and other objects are attained by the lubrication apparatus and duplex pump unit therefor, parts, combinations, and sub-combinations which comprise the present invention or discovery, and the nature of which is set forth in the following general statement, and preferred embodiments of which together with their mode of use are set forth in the following description, and which are particularly and distinctly pointed out and set forth in the appended claims forming part hereof.

The nature of the present invention or discovery may be stated in general terms as including in an internal combustion engine and the like including one or more shafts each rotatable in a bearing and constituting parts requiring lubrication, lubrication apparatus for the parts including walls forming a sump chamber below the parts, walls forming an auxiliary lubricant supply chamber outside of the sump chamber and preferably surrounding the sump chamber. The sump chamber is adapted for containing the main fluid lubricant supply, usually oil for the parts, and the auxiliary lubricant supply chamber is adapted for containing an auxiliary fluid

2

lubricant supply, and there is provided in association with the walls of the two chambers, an overflow communicating duct or passageway between the sump chamber and the auxiliary lubricant supply chamber.

Within the sump chamber there is located a main lubricant pump, and an auxiliary lubricant pump. Walls form an auxiliary lubricant transfer chamber and a thermostat chamber having a common wall between each other and the common wall having a valve seat opening formed therein, and a valve is arranged for opening and closing the valve seat opening. A thermostat located in the thermostat chamber is arranged to open and close the valve at and below a particular temperature of the media surrounding the thermostat. The suction line for the main pump passes through the thermostat chamber, and the discharge line for the main pump communicates with the parts requiring lubrication. The suction line for the auxiliary pump delivers fluid or flowable lubricant from the auxiliary lubricant supply chamber to the auxiliary pump, and the discharge line for the auxiliary pump communicates from the auxiliary pump through the auxiliary lubricant transfer chamber and over the valve and to the auxiliary lubricant supply chamber.

Preferably, the main and auxiliary pumps and the walls forming the thermostat chamber and the auxiliary lubricant transfer chamber are associated with each other and with other parts as a duplex pump unit which is detachable from the engine or similar apparatus equipped therewith.

By way of example, embodiments of the improved lubrication apparatus and the improved duplex pump unit thereof of the present invention or discovery, and parts thereof are illustrated in the accompanying drawings forming part hereof in which:

Fig. 1 is an end elevational view of an internal combustion engine including the improved lubrication apparatus;

Fig. 2 is a side elevational view, with portions broken away and shown in section of one of the improved duplex pump units for the improved lubrication apparatus, the pump unit being shown detached from the engine;

Fig. 3 is a fragmentary reduced transverse sectional view of the improved pump unit as on line 3—3, Fig. 2;

Fig. 4 is another fragmentary reduced transverse sectional view of the improved pump unit as on line 4—4, Fig. 2;

Fig. 5 is a fragmentary reduced vertical sectional view of the improved pump unit as on line 5—5, Fig. 2;

Fig. 6 is an enlarged fragmentary side elevational view of the engine, looking in the direction of arrows 6—6, Fig. 1, parts being broken away and shown in section;

Fig. 7 is a transverse sectional view thereof as on line 7—7, Fig. 6, lower portions being broken away and shown in transverse section as on line 10 1a—1a, Fig. 6; and

Fig. 8 is an oblique sectional view thereof as on line 8—8, Fig. 7.

Similar numerals refer to similar parts throughout the drawings.

The internal combustion engine illustrated in Figs. 1, 6, 7, and 8, and indicated generally by 10, includes one embodiment of the improved lubrication apparatus of the present invention or discovery, and the illustrated embodiment of the improved lubrication apparatus includes a double-chambered oil pan indicated generally by 11 depending below the cylinder block indicated generally by 12.

As shown, the double-chambered oil pan 11 is formed by a unitary lower casing 13 which is located below and separably connected with the lower end of a unitary intermediate casing 14. The unitary casings 13 and 14 may be made of cast metal usual in internal combustion engine construction, such as aluminum alloy or cast iron. The upper end of the intermediate casing 14 has outturned side and end flanges 15 connected in a usual manner by cap screws 16 with outturned side and end flanges 17 on the lower end of the cylinder block 12. The parting plane of the flanges 15 and 17 is at right angles to the longitudinal axis of the engine cylinders, and is usually horizontal in use.

The casing 13 furthermore includes upper outturned side and end flanges 18 connected with an outturned side flange 19 and inturned side and end flanges 20 on the lower end of the casing 14, by usual stud and bolt means 21, and the parting plane between the flanges 18 and the flanges 19 and 20 is oblique with respect to the parting plane between the flanges 15 and the flanges 17.

The casing 13 furthermore includes an outer bottom wall 22, opposite outer side walls 23 and 24, opposite outer end walls 25 and 26, and an outer top wall 27 forming an enlarged chamber 28 which has a transversely rectangular cross section as shown in Fig. 7. Within the enlarged chamber 28, the casing 13 also includes an inner bottom wall 29, inner side walls 30 and 31, and inner end walls 32 and 33 forming a center sump chamber 34. The inner bottom wall 29 is spaced above the outer bottom wall 22, and the inner side walls 30 and 31 are spaced respectively a substantial distance laterally from the outer side walls 23 and 24, and the inner end walls 32 and 33 are spaced respectively a substantial distance laterally from the outer end walls 25 and 26. The inner side walls 30 and 31, and the outer end walls 25 and 26 extend upwardly above the outer top wall 27 and terminate in the flanges 18.

The casing 13 furthermore includes a plurality of overflow duct walls respectively indicated by 35a, 35b, and 35c and respectively forming overflow ducts 36a, 36b, and 36c communicating respectively between upper overflow openings 37a, 37b, and 37c formed in the inner side wall 31 and lower overflow openings 38a, 38b, and 38c formed in the top wall 27.

The inner side wall 30 of the casing 11 above 75

the top wall 27 is formed with a pair of bosses respectively indicated by 39a and 39b and having bores 40a and 40b communicating at their upper ends through the flange 18 and at their lower ends into the chamber 28. The casing 14 includes a side wall 41 above the inner side wall 30 of the casing 11, and the intermediate casing side wall 41 is formed with a pair of bosses respectively indicated by 42a and 42b, and having respectively elbow ducts 43a and 43b formed therein. The lower openings of the elbow ducts 43a and 43b register respectively with the upper ends of the bores 40a and 40b.

Casing 13 furthermore includes tubular walls 44 forming a drain tube 45 for the center sump chamber 34. The outer end of the drain tube 45 terminates in the outer end wall 25 in an internally threaded opening 46 in which is screwed a drain plug 47. The inner end of the drain tube 45 communicatingly connects with an opening formed in the lower border portion of the inner end wall 32 below the inner bottom wall 29, and the inner bottom wall 29 terminates within the chamber 34 at an end 29—1 spaced from the end wall 33, whereby communication is effected between the sump chamber 34, below the bottom wall 29 and above the bottom wall 22 with the drain tube 45, as best shown in Figs. 6 and 7. There is furthermore provided in the outer end wall 25 an internally threaded drain opening 48 in which is screwed a drain plug 49, the drain opening 48 being for the chamber 28.

The inner side walls 30 and 31 of the casing 13 are provided respectively on their inner faces with flanges 50 and 51 extending transversely towards each other and longitudinally of the side walls 30 and 31. An oil sludge filter indicated generally by 52 is located and supported in the lower end of the sump chamber 34, and as shown includes a top plate 53 separably secured on the top faces of the flanges 50 and 51 by cap screws 54. Side, end, and bottom walls formed of fine screening 55 have the upper edges of the side and end walls secured to the lower face of the top plate 53. The top plate 53 has formed therein adjacent the side wall 30 an opening 56 for a purpose hereinafter described in detail.

In the bores of the bosses 39a and 39b there are located respectively the upper end portions of tubes 57a and 57b whose upper extremities are externally threaded and screwed respectively in the internally threaded lower openings of the elbows 43a and 43b of the registering bosses 42a and 42b. The lower end of each tube 57a and 57b is located adjacent the inner face of the outer bottom wall 22 of the casing 13. Adjacent the side wall 24 of the casing 13 there is provided on the upper face of the top wall 27 a boss 58 having a bore in which is fitted a sleeve 59 through which extends an oil level gauge stick 60 having an upper end handle 61.

The cylinder block 12 includes a lower crank case portion 62, the lower opening of which communicates with the upper opening of the intermediate casing 14, and the lower opening of the intermediate casing 14 communicates with the upper opening of the lower casing 13.

The improved lubrication apparatus of the present invention or discovery furthermore includes an improved unitary duplex pump unit, one embodiment of which is illustrated and indicated generally by 63 and which extends from the lower end of the compartment 64 of the crank case portion 62 of the cylinder block 12

through the compartment 65 of the intermediate casing 14 and into the sump chamber 34.

The improved duplex pump unit 63 is illustrated in Figs. 6, 7, and 8, in its installed position in the internal combustion engine 10. In Figs. 2 to 5, inclusive, the improved duplex pump unit 63 is illustrated detached from the engine 10, with portions shown broken away and in various sections for clearly illustrating the details of construction.

The improved duplex pump unit 63 includes an upper main pump housing 66, an intermediate auxiliary pump housing 67 and a lower main pump suction housing 68. The upper housing 66 is connected at its lower end 69 with the upper end 70 of the intermediate housing 67 as by stud and nut means 71. The lower end 72 of the intermediate housing 67 is connected with the upper end of the lower housing 68 as by stud and nut means 73. The upper housing 66 is formed with a bearing bore 74, and the intermediate housing 67 is formed with a bearing bore 75, and the bearing bores 74 and 75 are coaxial with each other and a duplex pump shaft 76 is journaled therein. The upper end 77 of the shaft 76 extends above the upper end of the upper housing 66, and a pinion 78 is secured thereon. Intermediate the ends of the upper housing 66 there is located an outwardly extending flange 79 having formed therein opposite apertures 80, and in the engine 10 the shanks of cap screws 81 extend through the apertures 80 and thereby the duplex pump unit 63 is secured to the lower end of the crank case portion 62 of the cylinder block 12, the pinion 78 being meshed with a gear on the cam shaft of the engine 10 in the usual manner, not shown.

In the lower end of the upper housing 66 there is formed a main pump chamber 82. Adjacent the shaft 76 in the chamber 82 there is located a stub shaft 83 which is journaled in the housing 66. A spur gear 84 is secured on the shaft 76 in the chamber 82 and a spur gear 85 is secured on the shaft 83 in the chamber 82, and the gears 84 and 85 are meshed with each other, and there is thus formed a main gear pump by the gears 84 and 85 and associated parts.

In the lower end of the intermediate housing 67 there is formed a combined auxiliary pump and auxiliary lubricant transfer chamber 86. The lower end 87 of the shaft 76 extends into the chamber 86 and has secured thereon a gear 88. At one side of the shaft 76 in the chamber 86, a stub shaft 89 is located and is journaled in the housing 67, and a gear 90 is secured on the shaft 89 and meshed with the gear 88, and there is thus formed an auxiliary gear pump by the gears 88 and 90 and associated parts.

The lower housing 68 includes walls forming a thermostat chamber 91 from the lower end of which extends a suction intake tube 92 for the main gear pump. The walls of the chamber 91 include a top wall 93 having formed therein at one side an outlet opening 94, Fig. 5. The intermediate housing 67 has formed therein an offset duct 95 having a lower end communicating with the outlet opening 94 of the housing 68. The upper end of the duct 95 communicates with the main pump chamber 82.

In the engine 10, the suction intake tube 92 extends through the opening 56 in the top plate 53 of the oil sludge filter 52.

The walls at the lower end 69 of the upper housing 66 forming the main pump chamber 82 are provided with a cylindrical discharge neck

96 with which is connected one end of a tube 97, the other end of which is connected in a usual manner with ducts (not shown) in the crank case portion 62 of the cylinder block 12 communicating with the engine bearings. As is usual in an internal combustion engine, the oil delivered to the engine bearings, after lubricating the same, drops down into the sump chamber 34.

The upper wall 93 of the lower housing 68 of the pump unit 63 has formed therein an opening 98 and a thermostat indicated generally by 99 includes a mounting flange 100 which is secured to the upper face of the wall 93. The thermostat 99 includes a U bracket 101 extending from the mounting flange 100 through the opening 98 in the wall 93 into the thermostat chamber 94 of the lower housing 68. The thermostat 99 as shown is of a usual bellows type, and includes a bellows 102 supported on the bracket 101 in the thermostat chamber 94, the bellows 102 being filled with air or other suitable gas. The lower end of the bellows 102 seats on the lower end bar 103 of the bracket 101, and from the upper end of the bellows 102 there extends a valve actuating tube 104. The mounting flange 100 is formed with a valve seat neck opening 105, and a cup valve 106 is secured on the upper end of the tube 104, and the peripheral flange 107 of the cup valve 106 is seated in the seat 105 under ordinary operating conditions. The cup valve 106 is a reciprocating valve actuated by the thermostat 99. For providing a safety factor in the operation of the improved lubrication apparatus, the disc portion 109 of the cup valve 106 has formed therein an oil bleed aperture 110.

The walls of the intermediate housing 67 have formed therein a suction opening 111 and a discharge opening 112. The openings 111 and 112 communicate with the chamber 86. The suction opening 111 has connected therewith one end of a suction tube 113, the other end of which is connected with the upper end of the nearest elbow duct 43a in the nearest boss 42a.

The discharge opening 112 is connected with one end of a discharge tube 114, the other end of which is connected with the upper end of the elbow duct 43b nearest end wall 26 of the casting 13.

In the operation of the internal combustion engine 10 including the improved lubrication apparatus hereof, the center sump chamber 34 is filled with lubricating oil to a level adjacent the overflow openings 37a, 37b, and 37c, and the surrounding chamber 28 is filled with lubricating oil to a level adjacent the top wall 27. The thermostat 99 is constructed and adjusted so that the valve 106 will start to open when the temperature of the surrounding media is in the neighborhood of 170° F. and will be fully open when the temperature is in the neighborhood of 205° F. Under usual operating conditions the main oil supply passes up from the sump chamber 34 through the suction intake tube 92 of the lower thermostat casing 68 of the duplex pump unit 63 passing around the thermostat 99 and thence through the main pump chamber 82 and to the bearings of the engine.

Meanwhile, oil flows up from the outer auxiliary lubricant supply chamber 28 through the tube 57a nearest the pump 63, which constitutes an outer end of the suction tube or line for the auxiliary pump formed by the gears 88 and 89 and their housing, and this oil under usual operating conditions of the engine 10 passes through the auxiliary pump and lubricant transfer cham-

ber 86 and out through the discharge tube 114 and the furthermost tube 57b constituting a discharge tube or line for the auxiliary pump. Thus, under usual operating conditions without the lubricating oil being overheated, the auxiliary oil supply in the compartment 28 is circulated from the compartment 28 through the auxiliary pump and back to the compartment 28.

When, however, the lubricating oil reaches a temperature of in the neighborhood of 170° F. due to usual operating conditions such as consumption of a portion of the main supply of lubricating oil in the center sump chamber 34, the valve 106 opens and the auxiliary oil is by-passed from the auxiliary pump and lubricant transfer chamber 86 into the thermostat chamber 91 where it is added to the main oil supply. The auxiliary oil thus added to the main oil supply fills the sump chamber 34 up to the overflow openings 37a, 37b and 37c from which the combined oil flows back into the outer chamber 28. When the temperature of the oil passing through the thermostat chamber 91 becomes lower than in the neighborhood of 170° F., the thermostat valve 106 closes and the usual operation of the engine is resumed.

In the several views Figs. 2 to 8, inclusive, the arrows indicate the direction of lubricant flow under ordinary operating conditions before the thermostat valve 106 opens.

It is to be noted that while lubricating oil is the usual lubricant used in internal combustion engines, any liquid or flowable lubricant such as a mixture of lubricating oil and other liquid or flowable material such as powdered graphite may be used in the improved lubricating apparatus of the present invention or discovery.

It is also to be noted that instead of the bellows thermostat actuating the valve 106, other thermostat means may be used such as a bi-metal thermostat which may control the operation of a servo-motor which in turn actuates the valve. From a broad standpoint the valve 106 may be defined as a thermostat actuated valve.

In the foregoing description, certain terms have been used for brevity, clearness, and understanding, but no unnecessary limitations are to be implied therefrom beyond the requirements of the prior art, because such words are used for descriptive purposes herein and are intended to be broadly construed.

Moreover, the embodiments of the improved construction illustrated and described herein are by way of example, and the scope of the present invention is not limited to the exact details of construction.

Having now described the invention or discovery, the construction, the operation, and use of preferred embodiments thereof, and the advantageous new and useful results obtained thereby; the new and useful constructions, and reasonable mechanical equivalents thereof obvious to those skilled in the art, are set forth in the appended claims.

I claim:

1. In lubrication apparatus for parts requiring lubrication in an internal combustion engine and the like, walls forming a sump chamber for a main flowable lubricant supply, walls forming an auxiliary lubricant supply chamber outside of the sump chamber for an auxiliary flowable lubricant supply, one of the sump chamber walls having formed therein an overflow opening effecting a communication between the sump chamber and the auxiliary lubricant supply chamber, a main

lubricant pump and an auxiliary lubricant pump in the sump chamber, walls forming an auxiliary lubricant transfer chamber and a thermostat chamber adjacent each other in the sump chamber, one of the walls of the auxiliary lubricant transfer chamber having formed therein a valve seat opening communicating with the thermostat chamber, a valve movable between closing and opening positions with respect to the valve seat opening, a thermostat located in the thermostat chamber and operatively connected with the valve for opening and closing the valve above and below a particular temperature of the media surrounding the thermostat, a suction line for the main pump communicating between the sump chamber through the thermostat chamber and to the main pump and a discharge line for the main pump communicating from the main pump to the parts requiring lubrication and thence to the sump chamber, a suction line for the auxiliary pump communicating from the auxiliary lubricant supply chamber to the auxiliary pump, and a discharge line for the auxiliary pump communicating from the auxiliary pump through the auxiliary lubricant transfer chamber and over the valve and to the auxiliary lubricant supply chamber.

2. In lubrication apparatus for parts requiring lubrication in an internal combustion engine and the like as set forth in claim 1, and in which the sump chamber is located below and in communication with the parts requiring lubrication.

3. In lubrication apparatus for parts requiring lubrication in an internal combustion engine and the like as set forth in claim 1, and in which some of the walls forming the auxiliary lubricant supply chamber are spaced from and extend around some of the walls forming the sump chamber and whereby the auxiliary lubricant supply chamber surrounds some of the walls of the sump chamber.

4. In lubrication apparatus for parts requiring lubrication in an internal combustion engine and the like as set forth in claim 1, and in which the wall of the auxiliary lubricant transfer chamber having the valve seat opening formed therein is a common wall of the lubricant transfer chamber and of the thermostat chamber.

5. In lubrication apparatus for parts requiring lubrication in an internal combustion engine and the like as set forth in claim 1, and in which the valve is a reciprocating valve.

6. In lubrication apparatus for parts requiring lubrication in an internal combustion engine and the like as set forth in claim 1, and in which the main pump and the auxiliary pump have common drive means.

7. In lubrication apparatus for parts requiring lubrication in an internal combustion engine and the like as set forth in claim 1, and in which the sump chamber is located below and in communication with the parts requiring lubrication, and in which some of the walls forming the auxiliary lubricant supply chamber are spaced from and extend around some of the walls forming the sump chamber and whereby the auxiliary lubricant supply chamber surrounds some of the walls of the sump chamber.

8. In lubrication apparatus for parts requiring lubrication in an internal combustion engine and the like as set forth in claim 1, and in which the valve is a reciprocating valve, and in which the thermostat is a bellows thermostat.

9. In lubrication apparatus for parts requiring lubrication in an internal combustion engine and

the like as set forth in claim 1, and in which the main pump and the auxiliary pump have common drive means, and in which the common drive means for the main pump and the auxiliary pump includes a rotary shaft and the main pump and the auxiliary pump each being a gear pump including two gears meshed with each other and one of the gears being mounted on the common shaft.

10. In lubrication apparatus for parts requiring lubrication in an internal combustion engine and the like as set forth in claim 1, and in which the main lubricant pump and the auxiliary lubricant pump, and the walls forming the auxiliary lubricant transfer chamber and the thermostat chamber, and the valve and thermostat are associated with each other and with common drive means for the pumps as a duplex pump unit separably mounted in the sump chamber.

11. In a duplex pump unit adapted for use in lubrication apparatus for parts requiring lubrication in an internal combustion engine and the like, a first pump and a second pump, housing and mounting walls including walls forming a chamber for each of the first and second pumps, common drive means for the first and second pumps operatively mounted in some of the housing and mounting walls, some of the housing and mounting walls forming a transfer chamber and a thermostat chamber adjacent each other, one of the walls of the transfer chamber having formed therein a valve seat opening communicating with the thermostat chamber, a valve movable between closing and opening positions with respect to the valve seat opening, a thermostat located in the thermostat chamber and operatively connected with the valve for opening and closing the valve above and below a particular temperature of the media surrounding the thermostat, one of the chamber walls of the first pump being provided with an opening communicating with the thermostat chamber and another of the chamber walls of the first pump being provided with another opening and one of the walls of the thermostat chamber being provided with an opening, one of the walls of the transfer chamber being provided with an opening and there being provided between walls

of the transfer chamber and walls of the second pump chamber an opening communicating between the second pump chamber and the transfer chamber and one of the walls of the second pump chamber being provided with an opening.

12. In a duplex pump unit adapted for use in lubrication apparatus for parts requiring lubrication in an internal combustion engine and the like as set forth in claim 11, and in which the wall of the transfer chamber having the valve seat opening formed therein is a common wall of the transfer chamber and of the thermostat chamber.

13. In a duplex pump unit adapted for use in lubrication apparatus for parts requiring lubrication in an internal combustion engine and the like as set forth in claim 11, and in which the common drive means for the first and second pumps includes a rotary shaft and the first and second pumps each being a gear pump including two gears meshed with each other and one of the gears being mounted on the common shaft, the gears of each pump being located in the chamber for the pump.

14. In a duplex pump unit adapted for use in lubrication apparatus for parts requiring lubrication in an internal combustion engine and the like as set forth in claim 11, and in which the valve is a reciprocating valve.

15. In a duplex pump unit adapted for use in lubrication apparatus for parts requiring lubrication in an internal combustion engine and the like as set forth in claim 11, and in which the valve is a reciprocating valve, and in which the thermostat is a bellows thermostat.
